United States Patent Office

Des. 208,736
Patented Sept. 26, 1967

208,736

FILM CARTRIDGE

John J. Van Acker, Chesterland, Ohio, assignor to Vari-
typer Corporation, Newark, N.J., a corporation of
Delaware

Filed Aug. 30, 1965, Ser. No. 86,761

Term of patent 14 years

(Cl. D61—1)

Fig. 3

Fig. 4

FIG. 1 is a left end, top and front perspective view of a film cartridge, showing my new design, the right end not shown being substantially a mirror image of the left end shown;

FIG. 2 is a rear, top and left end perspective view;

FIG. 3 is a front elevation; and

FIG. 4 is a bottom plan thereof.

I claim:

The ornamental design for a film cartridge, substantially as shown and described.
